(71) Applicant: **Apple Inc.**, Cupertino, CA (US)

FOREIGN PATENT DOCUMENTS

(72) Inventors: **Kevin Will Chen**, Cupertino, CA (US);
Alan C. Dye, San Francisco, CA (US);
Aurelio Guzmán, San Jose, CA (US);
Bon Min, Seoul (KR); **Christopher I. Wilson**, San Francisco, CA (US)

CH	221643	6/1942
CN	303337230 S	8/2015
JP	1568367	1/2017

(73) Assignee: **Apple Inc.**, Cupertino, CA (US)

(**) Term: **15 Years**

(21) Appl. No.: **29/846,620**

(22) Filed: **Jul. 18, 2022**

Related U.S. Application Data

(63) Continuation of application No. 29/817,113, filed on Nov. 29, 2021, now Pat. No. Des. 958,175, and a continuation of application No. 29/817,067, filed on Nov. 29, 2021, now Pat. No. Des. 958,174, which is a continuation of application No. 29/692,897, filed on May 29, 2019, now Pat. No. Des. 937,293, said application No. 29/817,113 is a continuation of application No. 29/692,897, filed on May 29, 2019, now Pat. No. Des. 937,293.

CLAIM

The ornamental design for an electronic device with graphical user interface, as shown and described.

DESCRIPTION

FIG. 1 is a front view of a display screen or portion thereof with graphical user interface showing the claimed design; and,

FIG. 2 is a front view of an electronic device having a display screen with graphical user interface, showing a second embodiment of the claimed design.

The outer broken lines in the figures show a display screen or portion thereof, or an electronic device having a display screen, and form no part of the claimed design. The other broken lines in the figures show portions of the graphical user interface that form no part of the claimed design.

1 Claim, 2 Drawing Sheets
